[57] CLAIM

The ornamental design for a bunk bed safety rail bracket, as shown and described.

DESCRIPTION

FIG. 1 is a perspective view of the bunk bed safety rail bracket with the broken line showing of a fragmented bunk bed being for illustrative purposes only and forming no part of the claimed design;

FIG. 2 is an enlarged perspective view thereof;

FIG. 3 is a side elevational view thereof, the opposite side being a mirror image thereof;

FIG. 4 is a front elevational view thereof, the rear side being a mirror image thereof; and,

FIG. 5 is a bottom plan elevational view thereof, the top plan view being a mirror image thereof.
